UNITED STATES PATENT OFFICE.

WALTER J. KIDD, OF SOUTH ORANGE, NEW JERSEY, ASSIGNOR TO THE
ALBO-CARBON LIGHT COMPANY, OF NEWARK, NEW JERSEY.

CARBURETING-LAMP.

SPECIFICATION forming part of Letters Patent No. 613,419, dated November 1, 1898.

Application filed May 10, 1897. Serial No. 835,860. (No model.)

To all whom it may concern:

Be it known that I, WALTER J. KIDD, a subject of the Queen of Great Britain, residing at South Orange, in the county of Essex and State of New Jersey, have invented a new and useful Carbureting-Lamp, of which the following is a specification.

My invention appertains to that class of carbureting-lamps in which heated gas is employed to vaporize a heavy hydrocarbon.

The objects of my invention are, first, to produce a cheap and simple form of carbureting-lamp suitable for attachment to existing chandeliers, gas-drops, or brackets; secondly, to provide a suitable construction both for the heating of the gas and the regulation of the extent of carburation of the same; thirdly, to provide a convenient and centrally-located shade-support.

Hitherto where heated gas has been made to impinge on the surface of naphthalene or other heavy hydrocarbon for the purpose of vaporizing the said hydrocarbon the gas has been raised to the required temperature either by the direct heat from the gas-flames coming in contact with the pipe or chamber in which the gas was heated or else the said pipe or chamber has been heated by a body of hot air retained around it by a heat-arrester or casing, there being a space between the casing and the pipe or chamber. A principal part of my invention consists in using conducted heat in place of the aforesaid direct heat or bath of hot air. I convey the heat from the gas-flames to the gas-heating pipe or tube by means of a simple heat-conducting device, in the form of a laterally-projecting plate having a close-fitting collar, surrounding and in contact with the gas-inlet pipe, the lateral flange being located above the level of the gas-flames and adjacent thereto. By this means the devices for heating the gas can be much simplified and are also much less expensive.

In the drawings, Figure 1 is a view, partly in section and partly in elevation, of my improved apparatus. Fig. 2 is a top view of the laterally-projecting heating-plate.

In the drawings similar numbers refer to similar parts.

The carbureting-lamp is attached by coupling 2 to the outlet 1 of an ordinary gas-fixture. The gas-channel is continued along the bent tube 3, elbow 4, and vertical descending tube or gas-heating pipe 5, which latter passes into the upper part of the shell 6 containing the naphthalene. Around the lower part of the vertical pipe 5 is rigidly and permanently attached a casing 7. This casing has an annular chamber 8 surrounding the gas-tube 5 and communicates both with the carbureting vessel and with the burner-tip 9. The shell 6 is detachably suspended at its neck 10 to the casing 7 by a screw inlet or opening 11, which engages the external screw-thread 12 on the casing 7. When the shell is screwed into position, it is made gas-tight by coming in contact with asbestos washer 13, which fits into a recess in the casing 7. The neck or opening at the top of the carbureting vessel 6 thus serves as a filling-orifice for replenishing the shell with naphthalene, and the shell being detachable in the manner described, may be conveniently removed for the purpose of refilling without disturbing the fixed upper portion.

Located at the upper part of the tube 5 and above the gas-flame (indicated by dotted lines at 14) is a horizontal flange or heat-conducting plate 15, which is preferably a light iron casting. A plan or top view of this plate is shown in Fig. 2. It will be noticed that in the form shown in the drawings the plate passes outside the gas-tube 5, being fitted thereon by a close-fitting collar 16 in continuous contact with the tube 5 for the purpose of more readily conducting and distributing the heat over the surface of the gas-heating tube. The heat-conducting plate projects on one side laterally and horizontally above the flame. At the edge farthest from the tube 5 the plate has a small flange 17, turning downward. This heat-conducting plate can be raised or lowered to any desired position on the tube 5 and can be fixed where required by means of a set-screw 18, which passes through the collar 16. In the case of a single gas-jet I prefer the construction shown in the drawings, in which it will be noticed that the heat-conducting plate projects on one side only of

the tube and is longer on the line of the axis coinciding with the horizontal length of the flame. When flames are located on various sides of the tube 5, a circular plate may be employed.

A vertical projection or shade-holder support 19 rises from the elbow 4. It is rigidly connected with the elbow and is preferably cast integral therewith. It supports a ring 20, 10 to which may be brazed or otherwise secured the ends of the shade-holder rods or wires 21, which clamp the lip of the shade 22. One of the shade-holder arms or wires is provided with a set-screw 23 to properly secure the shade. The shade-holder, with its ring 20, 15 can be readily taken off the shade-holder support 19. A loose thread may engage the two parts, or, as shown in the drawings, the vertical projection may be wedge-shaped and the 20 interior of the ring made to fit the wedge-shaped projection. In this way the shade and shade-holder can be instantly lifted off the fixed support, while at the same time they are steadily secured when in position. The shade- 25 holder is in this way detachably connected with its fixed support.

The operation will be as follows: After the lamp is connected to the gas-fixture outlet 1 the gas will pass through tubes 3 and 5 into 30 the carbureting vessel 6, and thence through the annular outlet-channel 8 to the burner-tip 9. The gas-flame highly heats the laterally-projecting heat-conducting plate 15, which, being in close contact with the tube 5 at the 35 collar 16, conducts the heat very effectively to the gas-tube 5. Some heat is also given to tube 5 by radiation from the flame. The incoming gas, passing through the highly-heated tube 5, becomes heated in turn and after melting and vaporizing the naphthalene contained in the shell 6 passes, with the vapor therefrom, to the burner-tip, giving to the flame the enrichment due to the hydrocarbon. The 40 laterally-projecting plate may be of any convenient shape and may be inclined more or less from the horizontal; but I prefer to employ a horizontal plate provided with a slight flange, as shown in the drawings. When the heat-conducting plate is raised to a higher 45 point above the flame, it receives less heat therefrom, and thus by raising or lowering the heat-conducting plate the gas may be heated less or more. In this way the extent 50 of generation of naphthalene-vapor can be 55 regulated.

In the construction herein described the laterally-projecting plate serves the special purpose of conveying heat by conduction to the gas-heating tube, and thus raises the gas

passing through said tube to a high temperature to enable it to melt the hydrocarbon in the carbureting vessel. It is thus a gas-heating device. It differs also from a bell or casing around the heated pipe in that it does not retain a bath of hot air around the pipe. A shallow horizontal heat-conducting plate has an advantage over a longer bell-shaped casing in that it enables the gas-heating tube to be shorter and thus makes the small lamp more compact. At the same time the construction is less expensive.

It will be noticed that the location of the shade-holder support and the bent gas-inlet tube 3 enables the shade to be both centrally located and also outside of the gas-channels forming part of the lamp. In this way an exceedingly simple, symmetrical, and compact construction of lamp is secured.

What I claim as my invention is—

1. In a carbureting-lamp, the combination, of a carbureting vessel, a gas-burner, a vertical descending gas-inlet tube 5, located above the carbureting vessel, said inlet-tube entering at the upper part of the vessel, and being rigidly attached to a burner-casing 7, supporting the vessel; and a laterally-projecting flange or heat-conducting plate, located around, and in continuous contact with, the said descending gas-inlet tube, at the collar of said flange, and situated above and in proximity to the gas-burner, and below the upper end of the vertical descending inlet-pipe 5, substantially as and for the purposes described.

2. In a carbureting-lamp, the combination, of a gas-burner; a vertical descending gas-inlet tube 5, located above the carbureting vessel, and entering at the upper part thereof; a laterally-projecting flange located around, and in continuous contact with, the said descending inlet-tube, at the collar of said flange, and situated above, and in proximity to, the gas-burner and below the upper portion of the vertical descending tube 5, said projecting flange being vertically adjustable upon the gas-heating pipe, by a sliding movement thereon, and by means of a suitable set-screw; and a carbureting vessel, located below the fixed upper portion, and detachably suspended therefrom at the screw-fitted neck, substantially as and for the purposes described.

In testimony whereof I affix my signature in the presence of two witnesses.

WALTER J. KIDD.
